UNITED STATES PATENT OFFICE

165,512

KEYBOARD GUARD FOR A TYPEWRITING
MACHINE

Theodore G. Clement, Rochester, N. Y., assignor
to L. C. Smith & Corona Typewriters, Inc.,
Syracuse, N. Y., a corporation of New York

Application July 21, 1951, Serial No. 15,982

Term of patent 14 years

(Cl. D64—11)

To all whom it may concern:

Be it known that I, Theodore G. Clement, a citizen of the United States of America and resident of Rochester, in the county of Monroe and State of New York, have invented a new, original, and ornamental Design for a Keyboard Guard for a Typewriting Machine, of which the following is a specification, reference being had to the accompanying drawings, forming a part thereof.

In the drawings:

Figure 1 is a front elevation of a keyboard guard for a typewriting machine, showing my new design;

Figure 2 is a side view thereof;

Figure 3 is a sectional view on the line 3—3 of Figure 1; and

Figure 4 is a plan view of the keyboard guard of Figure 1.

I claim:

The ornamental design for a keyboard guard for a typewriting machine, substantially as shown.

THEODORE G. CLEMENT.
